ABSTRACT OF THE DISCLOSURE

This invention relates to a method for improving the electrical and thermal efficiency of electrical and thermal contact surfaces, such as between clamps and electrodes, which comprises inserting malleable graphite between such surfaces in a quantity which is at least sufficient to occupy any areas of such surface where there is otherwise no contact.

This invention relates to a process for improving the efficiencies of electrical or thermal contacts and more particularly relates to a process for increasing the electrical and thermal efficiency of metal clamps such as are used as connectors to graphite anodes.

The problem of obtaining and maintaining good electrical contact between an electrical clamp and an electrode has long been recognized and numerous solutions have been proposed therefor. Such solutions include the use of carefully mated and machined electrode and clamp surfaces and the use of increased clamping pressure. Also this approach has proven time consuming and unduly expensive, and has not provided a highly efficient clamping means.

It is an object of this invention to provide a process whereby the efficiency of electrical and thermal contacts may be improved. A further object is to provide a process whereby electrical clamps may be contacted with electrodes to provide improved electrical and thermal efficiencies. A further object is to provide a method whereby such increased thermal and electrical efficiency may be quickly, easily, and economically achieved. These and other objects and advantages will become obvious from a reading of the following detailed description.

It has now been discovered that the electrical and thermal conductivity at the interface between electrical or thermal contact faces may be greatly enhanced by providing between such contact surfaces a quantity of malleable graphite either in the particulate vermicular form or in partially compressed form. Such graphite is placed between the contact surfaces prior to the application of clamping pressure. Under usual clamping pressure, the malleable graphite flows to fill any spaces between the contact faces to thereby provide a highly conductive contact where substantially less contact would otherwise have been present.

The vermicular graphite used herein is a compressible form of expanded graphite prepared by introducing an intercalating agent between the laminae of natural or synthetic graphite and expanding such treated graphite by heating. For example, a heat-expandable graphite may be prepared by contacting particles of natural flake graphite with fuming nitric acid, fuming sulfuric acid, mixtures of concentrated nitric and sulfuric acids, perhalo acids, or the like, for a period of a minute or so. The treated graphite particles may then be washed free of excess intercalating agent and dried if desired. The heat-expandable graphite thus prepared may be expanded from 20 to 600 times, usually between 200 and 600 times its original volume by heating, e.g. to 500° C. or more. Such expanded graphite is usually in light weight particulate, vermicular, worm-like form, usually has a bulk density of 0.005 to 0.01

2

gm./cc. and is easily malleable and compressible into any desired shape up to a density approaching the theoretical of about 2.26 gm./cc. This light weight vermicular form of graphite may be compressed into compacts having a density of up to about 0.07 gm./cc. and while still retaining its ability to deform and flow under relatively low pressures, e.g. pressures of 15 p.s.i. to 100 p.s.i.

The term "malleable graphite" when used herein, therefore, refers to vermicular graphite in either particulate form or in the form of a compact having a density up to about 1.9 gm./cc. and which is deformable under pressure.

The amount of malleable graphite employed between two contact surfaces such as between a clamp and an electrode depends largely upon the roughness and irregularity of the surfaces to be joined. For the optimum efficiency, sufficient malleable graphite is employed to fill all gaps and discontinuities between the clamp and the electrode upon tightening the clamp, and leave little if any malleable graphite between the clamp and the electrode at points of natural contact. For example, when employed with serrated clamps, as frequently used to conduct current to electrographite anodes for the electrolytic production of magnesium metal, sufficient malleable graphite is used to fill the notched portions of the clamp face to thereby give a more complete contact between the clamp face and the anode surface. Preferably, however, little or no malleable graphite remains between the clamp teeth and the electrographite to reduce the normal contact therebetween. Malleable graphite employed in this manner greatly increases clamping efficiency, reduces voltage drop across the clamp interface and improves heat dissipation from the electrode.

Additional advantages are achieved by employing malleable graphite between an electrode and the clamp therefore. If, as in many electrolytic processes where electrographite electrodes are employed, corrosive gases are given off, such gases pass through the electrographite and attack the face of the clamp. This causes loss in conductivity, periodic shutdown to clean the clamp and, eventually clamp destruction. This problem is greatly reduced or eliminated by the use of malleable graphite which is highly impervious to gases and does not itself corrode.

Another problem frequently encountered with electrographite is the necessity of completely removing the clamp before the electrode can be positioned by moving it up or down within the cell or bath. Malleable graphite placed between the clamp and the electrographite provides sufficient lubricity to enable the clamp to be merely loosened and the electrode moved up or down without damage.

Malleable graphite, if in cohered or compacted form, may be wrapped around the electrode and the clamp placed around the graphite layer. If the malleable graphite is in particulate, vermicular form, it is applied between the clamp and the electrode prior to tightening of the clamp.

The electrical junction resistance of battery cathodes is likewise improved by employing cathodes containing at least an outer surface of compressed vermicular graphite. Such graphite provides a more efficient contact surface between the cathode and the depolarizing mixture and thereby lowers the junction resistance at the cathode face. Such efficiency is even further increased by employing a depolarizing mixture which contains particulate vermicular graphite.

The following examples are provided to more fully illustrate the invention but are not to be construed as being limiting thereto.

Example 1

A 1" x 1/4" x 10 1/2" piece of commercial electrographite impregnated with phenol-formaldehyde resin was em-

ployed as the electrode in the following tests. At right angles across the 1 inch face of the electrographite was clamped a flat steel plate 1 inch wide. The 1 inch square portion of the steel plate which contacted the electrographite was sanded to provide good contact. Clamping force between the steel plate and the electrode was obtained and measured by a force gauge. A constant D.C. current flow of 1.35 amps was maintained between the electrode and the steel clamp. Voltage drop between such clamp and electrode was measured between contact points 1 inch apart.

In separate, but otherwise similar experiments, various thicknesses and forms of malleable graphite were inserted between such electrode and the one square inch of metal surface contact area of the clamp and similar voltage drop measurements were made. Thus the results of such uses of malleable graphite were compared with the use of no malleable graphite. The results obtained are shown in the following Table I.

TABLE I

Test No.	Malleable graphite between clamp and electrode	Millivolt drop between clamp face and electrode at following clamp pressures, p.s.i.									
		10	20	30	40	50	60	70	80	90	100
Control	None	72.5	45.6	34.9	28.4	23.3	20.3	17.3	15.8	14.5	13.4
1	0.017 in. thickness of uniaxially compressed foil with high conductivity axis parallel to clamp face (1.82 gm./cc.)	62.4	53.2	45.2	38.7	32.4	26.6	22.8	20.3	18.6	16.8
2	0.032 in. thickness of uniaxially compressed foil with high conductivity axis perpendicular to clamp face (1.8 gm./cc.)	50.7	33.5	25.7	22.0	18.1	16.4	15.2	12.9	12.1	11.4
3	Vermicular graphite having density of 0.005 gm./cc. Final average thickness after 100 p.s.i. clamp pressure was 0.007 in.	22.8	15.4	12.4	9.5	8.5	7.6	6.9	6.4	6.1	5.6

Example 2

The same procedure and equipment employed in Example 1 was used except the face of the steel clamp was serrated with straight parallel grooves approximating the profile of an American Standard screw thread for a $\frac{1}{2}$ inch bolt. The results obtained are shown in the following Table II.

were partially immersed in a 700° C. molten salt bath containing $MgCl_2$. As necessary the anodes were lowered into the molten salt bath and the clamps were moved up the anode stem.

For purposes of comparison, Clamp A with malleable graphite foil and Clamp B without such foil (control) were operated in parallel and the voltage drop between

TABLE II

Test No.	Malleable graphite between clamp and electrode	Millivolt drop between clamp face and electrode at following clamp pressures, p.s.i.									
		10	20	30	40	50	60	70	80	90	100
Control	None	74.1	60.7	45.2	35.2	20.2	24.8	22.5	20.4	18.7	17.7
1	0.112 in. thickness of uniaxially compressed foil having a density of 0.06 gm./cc. and high conductivity axis parallel to clamp face.	70.0	36.5	22.4	17.5	15.4	14.3	12.9	11.7	10.7	9.9

Example 3

In order to demonstrate the increased thermal conductivity between two conductive materials when malleable graphite is employed between such materials, a 40 p.s.i. clamping force was employed between two sanded, smooth, electrographite blocks. The upper block is designated as Block A and the lower block as Block B. In one instance no malleable graphite was employed between the blocks and in the other instance a layer of vermicular graphite having an initial bulk density of 0.005 gm./cc. was employed which after compression between the blocks formed a film having a thickness of 0.005 inch. An electrical heater was applied to the upper surface of the upper graphite block and the central temperatures of each block was recorded as shown in Table III.

each clamp and anode was measured. Results are shown in the following Table IV.

TABLE IV

Days of operation	Voltage drop in millivolts	
	Clamp A (0.077 foil)	Clamp B (no foil)
55	1 0.080	1 0.080
16	0.053	0.105
21		
28	0.053	
40	0.053	
42		0.300
45	0.050	

50 55 60 65 70 75 1 The higher initial resistance of clamp A was due to the use of a thicker graphite foil to demonstrate the effect of a corrosive atmosphere upon clamps with and without such graphite foil.

At the end of 45 days, the clamp having no foil showed extensive evidence of corrosion on the clamp face while the clamp containing graphite foil showed no significant quantity of corrosion.

Various modifications can be made in the present invention without departing from the spirit or scope thereof for it is understood that we limit ourselves only as defined in the appended claims.

We claim:

1. A process for improving the electrical and thermal efficiency of electrical and thermal contact surfaces which comprises applying vermicular graphite in particulate form or in compacted form having a density up to about

Run No.	Malleable graphite at interface	Temperature, $^{\circ}$ C.		
		Block A	Block B	Difference
Control	None	113	105	8
		196	175	21
		202	180	22
		217	192	25
		238	209	29
		264	222	32
1	Vermicular graphite compressed to 0.005 in. thickness.	113	107	6
		162.5	151.5	11
		194	180	14
		214	197	17
		235	216	19

1.9 gm./cc. between said surfaces in a quantity at least sufficient to occupy any areas of said surfaces where there is otherwise no contact.

2. The process of claim 1 wherein the graphite has a bulk density of up to about 0.07 gm./cc.

3. The process of claim 1 wherein the graphite is in cohered anisotropic form.

4. The process of claim 1 and including the step of applying sufficient pressure to said surfaces to cause deformation and flow of the graphite between such surfaces.

5. A process for providing improved electrical and thermal contact between metal clamps and graphite anodes which comprises inserting between such clamp and such anodes a quantity of vermicular graphite in particulate form or in compacted form having a density up to about 1.9 gm./cc. sufficient to form a graphite layer of between about 0.0005 inch and 0.5 inch thick when subjected to clamping pressure and exerting a clamping pressure of at least 15 p.s.i. upon such graphite.

6. The process of claim 5 wherein the graphite has a density of from about 0.005 gm./cc. to about 1.9 gm./cc. prior to being subjected to clamping pressure.

7. The process of claim 5 wherein the graphite is in vermicular form prior to exerting said clamping pressure thereon.
